Atty.

UNITED STATES PATENT OFFICE

2,063,318

PIPE WRENCH

John V. Larson, Chicago, Ill.

Application August 26, 1935, Serial No. 37,822

3 Claims. (Cl. 81—104)

This invention relates to that type of pipe wrenches constituting the subject matter of my former Patent No. 1,602,619 dated Oct. 12, 1926, in which the adjustable jaw and its operating sleeve nut are operatively associated with the main or stationary jaw of the wrench by an intermediate rocker yoke, of an angular formation, pivotally mounted in the stationary jaw to provide limited independent movement between the respective wrench jaws in attaining an effective initial holding grip on the pipe operated on, previous to a forcible turning operation of said pipe, and this improvement has for its objects:

To provide a structural formation of the rocker yoke by which the operating sleeve nut of the wrench is carried, and whereby said yoke is adapted to strengthen and reinforce the forward guide sleeve of the main jaw against the excessive strain to which said sleeve is subjected in actual use of the wrench.

To provide a structural formation of an upstanding member of the rocker yoke aforesaid and the parts of the wrench coating therewith, whereby the adjusting sleeve nut of the wrench is maintained in place against accidental displacement and loss, when the adjustable wrench jaw is separated from the other wrench parts for cleaning, repair, etc., all as will hereinafter more fully appear.

30 In the accompanying drawing:

Fig. 1 is a side elevation of an adjustable pipe wrench embodying the present improvements and showing the parts in their normal inactive positions.

35 Fig. 2 is a companion side elevation illustrating the wrench members in position for actual use on a section of pipe or the like.

Fig. 3 is a transverse section on line 3—3 Fig. 1.

Fig. 4 is a fragmentary longitudinal sectional elevation illustrating the internal construction of the stationary jaw member, the adjustable jaw member being removed from position therein.

Fig. 5 is a transverse section on line 5—5 Fig. 4.

Fig. 6 is a perspective view of the rocker yoke 45 in a detached condition.

Like reference numerals indicate like parts in the several views.

The general construction and operation of the wrench members in this improvement are similar in most respects to that of the wrench members set forth in my aforesaid Letters Patent No. 1,602,619, with the present construction comprising main wrench member the body portion 1 of 55 which is formed with a rearwardly extending

shank portion 2 constituting an operating handle or lever of the wrench.

At its forward end said body portion carries the fixed gripper jaw 3, usually of a serrated formation, and in addition is formed with a pair of 5 tubular guide brackets 4 and 5 in angular relation to the fixed jaw 3, with such brackets providing means in which the shank portion of the herein-after described adjustable wrench member is mounted and guided in proper aligned relation to 10 the main body and its fixed gripper jaw 3 aforesaid.

The brackets 4 and 5 are arranged in spaced relation, one to the other, to provide an intervening space for the reception and positioning of 15 the usual sleeve nut 6 by which the movable wrench jaw is adjusted to and from the fixed gripper jaw 3 aforesaid, and in addition the described separation of the brackets 4 and 5 provides space for the reception and pivotal mounting 20 of the herein-after described rocker yoke of the wrench.

The adjustable wrench member, heretofore referred to, comprises a carrying head 7 for the movable gripper jaw 8 of the wrench, and is 25 formed with an elongated bar or shank 9 in angular relation to the jaw 7, with the top and bottom edges of the bar or shank screw threaded for operative engagement with the aforesaid operating sleeve nut 6, and with its flat sides adapted 30 for sliding engagement with the inner side faces of the bracket members 4 and 5, with a view to resist any lateral stress in the shank or bar in actual use of the wrench, while permitting of the usual rocking movements of the movable jaw 35 member in the usual manipulation of the wrench in actual use. Such construction and movement of parts is usual in the present type of pipe wrenches, and more particularly in the type of wrench set forth in my aforesaid Patent No. 40 1,602,619.

The rocker member or yoke, heretofore referred to, is in many particulars similar to the rocker yoke of my aforesaid patent, having a like angular shape and comprising a construction as follows: 45

A main portion 10 of a disk shape, orificed to have a snug sliding fit upon the screw threaded shank 9 of the adjustable gripper jaw member, and in this improvement said rocker yoke is formed with rearwardly extending tongues 11 at 50 the respective sides of its central orifice adapted to project into the interior of the adjusting sleeve nut 6, and sliding contact with the sides of the shank 9 of the gripper jaw member, and adapted to engage and maintain said sleeve nut in proper 55

- relation with remaining parts of the wrench after a removal of the adjustable gripper jaw member is made for the purpose of cleaning, repair and like operations on the wrench parts.
- 5 The object being to avoid trouble due to loss of time and labor in recovering the sleeve nut, when the same in a disassemblage of the wrench parts the sleeve nut falls to the floor and for a time is lost.
- 10 The other, and rearwardly extending portion 12 of the angularly formed rocker or yoke member is of a flat formation, and in the present improvement is formed with an upturned abutment lug 13 having limited movement to and from 15 abutment shoulders 14 provided in the forward ends of the side webs of the rearward bracket member 5. The purpose being, with the lug 13 in contact with the shoulders 14 aforesaid, the rocker or yoke member is rigidly held against 20 further independent movement, and thus constitutes a brace for the comparatively thin side walls of the forward bracket member 4, to strengthen the same under the strain which is imposed on said walls in the actual use of the 25 wrench.

As in my former patented construction the rocker or yoke member is provided at the intersection of its angularly disposed members 10 and 12 with a semi-circular pivot lug 15 adapted to 30 provide limited pivotal movement to said rocker or yoke member in like pivot recesses formed in the rear edges of the side walls for the forward bracket member 4 near the lower portions thereof. While in the preferred construction shown 35 in Figs. 1, 2, 4 and 6, operative connection between the operating sleeve nut 6 and the rocker or yoke member is attained by a longitudinal groove 16 formed in the upper face of the rearwardly extending member 12 of said yoke member and into which the lowermost portion of said 40 sleeve nut fits and has operative engagement.

A normal tendency to move the movable gripper jaw 8 and its associated parts into a normally closed relation of the gripper jaws, shown in Fig. 45 1, is maintained by a leaf spring 17 secured at its rear end on the upper face of the wrench handle 2, with its free and forward end having resilient bearing against the under face of the rearwardly extending member 12 of the yoke member. Said

arrangement requiring a manual separation of said jaws in an initial application of the wrench to a section of pipe or like article that is to be operated on.

Having thus fully described my invention what 5 I claim as new, is:—

1. In a wrench of the type described, the combination of a main jaw member provided with an operating handle at its rear end and a pair of tubular guide brackets near its forward end, said 10 brackets being arranged in spaced relation with the forward bracket formed with a pivot recess in the lower portion of its rear wall and the rearward bracket formed with an abutment shoulder in its forward end adjacent to the lower portion of the bracket, an adjustable jaw member having a screw-threaded shank adapted for sliding and rocking engagement in said guide brackets, a sleeve nut arranged between said guide brackets and having operative engagement with the screw 20 threaded shank of the adjustable jaw member, and a rocker yoke of an angular form arranged between the aforesaid guide brackets and comprising a forward centrally orificed portion having a sliding fit on the screw threaded shank of said 25 adjustable jaw member, and a rearwardly extending portion of said rocker yoke being formed with a holding flange at its rear end having operative engagement with the lower side of the sleeve nut aforesaid, the rear end of said rocker 30 yoke having sliding movement against the forward end of the rearward guide bracket with its rear end adapted to contact with the aforesaid abutment of the rear guide bracket to limit the 35 movement of the rocker yoke.

2. A wrench of the construction as set forth in claim 1, wherein the rear end of the rearwardly extending portion of the rocker yoke is formed with an upturned lug for contact with the aforesaid stop shoulder of the rearward guide 40 bracket.

3. A wrench of the construction as set forth in claim 1, wherein the orificed portion of the rocker yoke is provided with rearwardly extending lugs at the sides of its orifice adapted to fit the bore of 45 the sleeve nut and maintain the same in proper position between the guide brackets in a disassembly of the wrench for repair, etc.

JOHN V. LARSON.
